UNITED STATES PATENT OFFICE.

WILLIAM J. FRASER, OF MILWAUKEE, WISCONSIN.

AUTOMATIC FIRE-EXTINGUISHER.

SPECIFICATION forming part of Letters Patent No. 439,293, dated October 28, 1890.

Application filed August 6, 1889. Serial No. 319,909. (No model.)

To all whom it may concern:

Be it known that I, WILLIAM J. FRASER, a citizen of the United States, residing at Milwaukee, in the county of Milwaukee and State of Wisconsin, have invented certain new and useful Improvements in Automatic Fire-Extinguishers; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to such systems of automatic fire-extinguishing apparatus as embody a series of pipes suitably supplied with water under pressure, and led along the ceilings of rooms to be protected, such pipes being provided at intervals with "sprinkler-heads." These sprinkler-heads are some form of device designed to automatically open the pipes for the admission of water to the room, and usually embody some special means for 20 spreading or distributing the water issuing from the pipes. Said sprinkler-heads are applied beneath or above or at the side of the pipes extending horizontally along the ceilings.

25 30 My improved sprinkler-head is shown in a portion of the drawings as applied beneath the horizontal pipes, and in a portion of the drawings as being applied above said pipes. It may also be applied to the side of the 35 pipes.

The object of this invention is to provide an apparatus the parts of which are small in number and simple in form.

In the accompanying drawings, Figure 1 is 40 a side view of one of the sprinkler-heads applied beneath the horizontal pipe. Fig. 2 is a similar view of one of the sprinkler-heads applied above the horizontal pipe. Figs. 3, 4, and 5 show modifications of the sprinkler-head.

45 Referring to Fig. 1, A is a horizontal pipe extending along the ceiling.

B is a branch pipe standing at right angles to the pipe A and joined thereto by a T-coupling A', or said branch pipe may be one of the arms of the T-coupling.

The pipe A may be of any suitable size to

convey a sufficient volume of water to a desired number of sprinkler-heads, and the branch pipe B may be of proper size to deliver into the room the volume of water desired in that portion of the room. Said pipe B is threaded exteriorly to receive the interiorly-threaded sleeve C' of the frame C. By thus applying the frame C upon the pipe B said frame may be adjusted longitudinally upon said pipe, so that whatever said frame supports is carried nearer to or farther from said pipe, depending upon the direction in which said frame and its sleeve are turned.

C² C³ are arms of the frame C, connected below by the horizontal bar C³.

D is a deflector held against the opening of the pipe B by the support D'. One end of said support rests upon a hip or equivalent device c², supported by the frame C below the deflector, while the opposite end of said support rests upon one end of a bar c³, pivoted at its middle to the frame C. Said bar is prevented from turning by the yoke D², having the laterally-directed arms C², one of which rests over the outer end of the bar C³ and the other of which rests over some portion of the frame C—as, for example, a projection c. Said projection c holds the lower portion of the yoke, and the upper arm d² of the yoke is made to hold the bar c³, so that the inner end of the latter is held immovably against the support D'.

E is an expansion device supported by the lower portion of the frame C, and arranged to force the yoke D² outward until it is freed from engagement with the bar c³ and the projection c. Said expansion device may be of any suitable form; but I prefer to use the form shown in the drawings. The same consists of a chamber E', filled with suitable expansive material, and a piston E², extending outward from said chamber toward or against the yoke D², so that when said expansive material expands the piston is driven forward to dislodge the yoke D². When the yoke D² is thus dislodged, the bar c³ yields and the support D' and the deflector E fall, thus allowing the water to flow from the pipe B. The deflector D may be made larger than the frame C, and the arms C² made to extend through slots d in said deflector. Then when said deflector falls it will be engaged by the

hip c^2 and the bar d^3 and held at a fixed distance from the opening of the pipe for the distribution of the water.

In Fig. 2 the head is in all respects like that shown in Fig. 1, excepting that it is reversed and located above the pipe A.

In Fig. 3 the frame C is applied to the end of the pipe B, as in Fig. 1, but the lower bar C^3 is omitted and one of the arms C^2 is shortened. The longer arm C^2 has at its lower end the inwardly-directed lug c^4 , and the shorter arm has the outwardly-directed lug c^5 . The expansion device E is similar to that shown in Fig. 1, but it is held in place by the lug c^4 and the yoke D^2 . One end or side of the expansion device rests upon the lug c^4 , while at the other end the upper arm of the yoke D^2 rests upon the lug c^5 , and the lower arm of said yoke rests against the lower side of said expansion device, so that said expansion device is held at that side by said yoke, and the piston E² is directed toward said yoke. Thus said expansion device is held stationary by said yoke so long as the latter is in engagement, but is released when said yoke is dislodged by the forward movement of the piston. The deflector D is then supported upon the expansion device E until said expansion device falls, whereupon said deflector also falls until it meets the hip c^2 and the lug c^5 .

In Fig. 4 the frame C is applied to the pipe B, as in Fig. 1, and the expansion device is put into a vertical position beside or as a part of one of the arms C^2 , the piston being directed upward. F is a support, having a point f bearing against a cap G, resting over the opening of the pipe B. Said support has another point f' bearing against the frame C or the expansion device E at a point below and at one side of the point f . Said support F has also an arm f^2 extending upward nearly over the point f' and beside the upper end of the expansion device E. A lug f^3 projects from the arm C opposite the arm f^2 , and a yoke D^2 is applied over said lug and said arm f^2 , so as to hold said support immovably in position. The rising of the piston of the expansion device under abnormal heat dislodges the yoke D^2 and allows the support F and the cap G to fall.

In Fig. 5 the parts are the same as in Fig. 4, excepting that the support F and expansion device E are united and together seated upon the frame C, as is said support alone in Fig. 4, and the yoke D^2 engages said lug f^3 and the upper end of the expansion-chamber E'. The upward movement of the piston E² dislodges the yoke D^2 and allows said expansion device, support F, and cap G to fall. In this form said expansion device may, in a certain sense, be regarded as a part of the support for the cap G.

I do not claim herein a wedge-block for holding a valve on its seat and a lock-pawl for holding said wedge-block in place until such pawl is released by an expansion device.

In another application filed by me Septem-

ber 6, 1889, and bearing Serial No. 323,216, I claim, broadly, the combination, with a water-supply pipe having an opening for the delivery of water, of a frame applied to said pipe, a valve placed over said opening, a part supported by said frame and constituting a portion of the support of said valve, and a movable member constituting another portion of the support of the valve, and an expansion device having a suitable part arranged to dislodge said movable member. The scope of the claims hereto appended is therefore to be limited to combinations embodying a yoke, the engaging portions of which are not hinged or coupled to the parts which they engage.

I claim as my invention—

1. In an automatic fire-extinguishing apparatus, the combination, with a pipe B, of a frame C, applied to the pipe B and a part resting over the opening of said pipe and held forcibly against said opening by another part, forming a support therefor and supported by said frame, a yoke holding said part constituting the support in position, and an expansion device to act directly upon said yoke, so as to force the latter out of engagement under abnormal heat, whereby the part closing the opening of said pipe is released, substantially as shown and described.

2. In an automatic fire-extinguishing apparatus, the combination, with a pipe B, of a frame C, applied to the pipe B and a part resting over the opening of said pipe and held forcibly against said opening by another part, forming a support therefor and supported by said frame, a yoke holding said part constituting the support in position, and an expansion device to act directly upon said yoke, so as to force the latter out of engagement under abnormal heat, whereby the part closing the opening of said pipe is released, such expansion device consisting of a chamber and piston, said chamber being filled with a suitable expansive material, substantially as shown and described.

3. In an automatic fire-extinguishing apparatus, the combination, with a pipe B, of a frame C, applied to the pipe B and a part resting over the opening of said pipe and held forcibly against said opening by another part, forming a support therefor and supported by said frame, a yoke holding said part constituting the support in position, and an expansion device so arranged with reference to said yoke as to act directly upon the latter and force it out of engagement under abnormal heat, whereby the part closing the opening of said pipe is released, said support, expansion device, and yoke being supported adjustably upon said pipe, substantially as shown and described.

4. In an automatic fire-extinguishing apparatus, the combination, with a pipe B, of a frame threaded adjustably around the end of said pipe, an expansion device resting upon one side of said frame and supported from

the other side of said frame by means of a yoke so located as to be forced out of engagement by the movement of a part of the expansion device, and a part applied over the opening of said pipe and held against said opening by a support from said expansion device, substantially as shown and described.

5. In an automatic fire-extinguishing apparatus, the combination, with a pipe B, of a frame threaded adjustably around the end of said pipe, an expansion-chamber resting upon one side of said frame and held against said frame at the other side by means of a

yoke and having a piston directed toward said yoke and being filled with a suitable expansive material, and a part applied over the opening of said pipe and supported by said expansion-chamber, substantially as shown and described.

10 In testimony whereof I affix my signature, 20 in presence of two witnesses, this 8th day of July, 1889.

WILLIAM J. FRASER.
